HIS ATTORNEY

UNITED STATES PATENT OFFICE.

WILLIAM GRUNOW, JR., OF NEW YORK, N. Y.

CAR-STARTER.

SPECIFICATION forming part of Letters Patent No. 470,753, dated March 15, 1892.

Application filed November 11, 1891. Serial No. 411,557. (No model.)

To all whom it may concern:

Be it known that I, WILLIAM GRUNOW, Jr., of New York, county and State of New York, have invented a new and useful Improvement 5 in Car-Starters, of which the following is a specification.

This invention relates to car-starters to be used principally on street-cars, although it may be used on railway-cars; and it consists 10 of a driver automatically set in operative position by a forward movement of the car just before stopping the same.

I will describe a car-starter embodying my invention, and then point out the novel features in claims.

In the accompanying drawings, Figure 1 is a side view of a car-starter embodying my invention. Fig. 2 is a top view thereof. Fig. 15 3 is a bottom view.

Referring by letter to the drawings, A designates a ratchet-wheel secured to the axle A' at a point between the car-wheels. I have here shown the ratchet-wheel A as made in two sections for convenience in attaching it 20 to an axle. The wheel A has an annular laterally-extending flange a on each side, and it also has outwardly-extending lugs on each side for a purpose hereinafter specified.

B designates a driver-arm adapted to have 25 a reciprocating movement longitudinally and also a slight rocking motion. This driver-arm extends loosely through a hole in a hanger B', secured to the bottom B² of a car, and its forward end has forwardly-projecting 30 fingers b resting on the periphery of the flanges a on the wheel A. The arm B carries a dog B³, adapted to engage at certain times with the teeth of the ratchet-wheel A. This dog is shown as pivoted to the arm between the 35 fingers b and resting on a transverse pin h or otherwise supported out of contact with the ratchet-teeth while in its forward position, as shown in Fig. 1. The fingers b are reduced in width toward their forward end, as at b', 40 so that when the driver-arm is forced rearward its free end will fall to a lower horizontal plane and allow the dog B³ to engage with the ratchet-teeth. A driver, here shown in the form of a coiled spring B⁴, surrounds the 45 driver-arm B between a shoulder B² on said arm and the bracket B'.

C is a movable part consisting of a setting-

bar having its rear end pivotally connected to the rear end of the driver-arm and supported in a lifter or yoke C', swinging on a stud 55 c, extending from the hanger B', and the yoke C' has an upwardly-extending arm C², with the upper end of which the brake-operating chain c' connects.

D is a dog pivoted on the stud c and having 60 its free end normally resting on a stop d, projecting from the hanger B'. The dog D is adapted to engage against one of the shoulders d' on the bar C when said bar is raised and the spring B⁴ is retracted. I preferably 65 make the bar C in two sections e e', pivotally connected together at e², and I provide an adjusting-screw e³, which extends through a tapped hole in a forward projection of the section e and bears against the under side of the 70 section e'. By means of this screw I can adjust the section e' vertically. The section e' of the bar C is bifurcate, and has an arm extending on each side of the ratchet-wheel A. Each arm of the section e' has a shoulder f, adapted to 75 engage with one of the pins a' on the wheel when the lever C is raised.

The operation of the device is as follows: When operating the brake to stop a car, the lifter or yoke C' is operated to raise the push-bar C, so that its shoulders f come in the line of rotation of the pins a'. The momentum of the car forces the bar C and arm B back, retracting or "loading" the spring, and the dog D engages against one of the shoulders d', 80 holding the parts in this rearward position while the car is at a standstill. At this time the dog B³ is in engagement with one of the teeth of the ratchet-wheel A. When it is desired to start the car, the brake-chain is released, allowing the yoke C' to fall to its downward position and permitting the bar C to fall 85 out of engagement with the dog D and release the tension of the spring B⁴, which expands and exerts its pressure against the 90 wheel A, and consequently starting it and the car.

I have described and shown a mechanism so attached to a car as to start it in one direction only; but it is obvious that two of 95 them may be employed, if desired.

Having described my invention, what I claim is—

1. In a car-starter, the combination, with a

car-axle, of a ratchet-wheel thereon, a driver-arm supported by the car, a dog on said arm adapted to engage with the ratchet-wheel, a spring for forcing said arm forward, and mechanism whereby said spring is retracted by the momentum of the car, substantially as specified.

2. In a car-starter, the combination, with an axle of a car, of a ratchet-wheel on said axle, a driver-arm supported from the car and constructed to engage at its forward end with said ratchet-wheel, a spring for forcing said driver-arm forward, means comprising a connection between the ratchet-wheel and said arm for forcing said arm rearward and retracting the spring, and means for holding said parts in their rearward position, substantially as specified.

3. In a car-starter, the combination, with an axle and the starter-arm and push-bar, of the ratchet-wheel on the axle, having the annular flanges and the outwardly-projecting pins or lugs, substantially as specified.

4. In a car-starter, the combination, with the car-axle, of the ratchet-wheel having the outwardly-projecting lugs, the driver-arm having the pivoted dog at its forward end, a spring for forcing said arm forward, a push-bar pivoted to the rear portion of said arm and con-

structed to engage at its forward portion with the lugs of the ratchet-wheel, a lifter for said push-bar operated from the brake-chain, and a pivoted dog for engaging with said bar when in its rearward position, substantially as specified.

5. In a car-starter, the combination, with the ratchet-wheel, the driver-arm, and the driver, of the push-bar pivotally connected to the driver-arm and consisting of two sections, one adjustable relatively to the other, substantially as specified.

6. In combination with a rotary part of a car, a driver-arm constructed to operate said rotary part, a setting device between the rotary part and driver-arm, movable into engagement with the rotary part, whereby the driver-arm is set in operative position by a forward movement of the car, and mechanism for shifting said setting device into engagement with the rotary part, substantially as specified.

In testimony whereof I have signed my name to this specification in the presence of two subscribing witnesses.
